UNITED STATES PATENT OFFICE.

THOMAS J. O'CONNOR, OF DALLAS, AND WARREN W. CULBERTSON, OF BOYCE, TEXAS.

RAILROAD-CROSSING.

1,297,721.

Specification of Letters Patent. Patented Mar. 18, 1919.

Application filed February 18, 1918. Serial No. 217,822.

To all whom it may concern:

Be it known that we, THOMAS J. O'CONNOR and WARREN W. CULBERTSON, citizens of the United States, residing at Dallas and Boyce, 5 in the counties of Dallas and Ellis and State of Texas, have invented certain new and useful Improvements in Railroad-Crossings, of which the following is a specification.

This invention relates to new and useful 10 improvements in railroad crossings.

Considerable difficulty has been experienced in the production and maintenance of railroad crossings and the life of the same is more or less limited according to the traffic, and further there is considerable objection 15 due to the noise made by the wheels as they pass over the gaps.

We propose to eliminate these objectionable features and to do so in a novel manner. 20 The invention contemplates both a noiseless and a long lived crossing, which will give a maximum wear and will prolong the life of the rolling stock by obviating the jar and vibration incidental to the 25 usual crossing; and further whereby the foundation of the crossing will be more easily maintained and require less repairing than is necessary where such foundation is subjected to severe shock and vibration.

30 In carrying out the invention movable members are provided at the intersections and so arranged as to form a continuous tread for the wheels of the train passing over the crossing. These members are automatically controlled so that when operated 35 to open the line over which the train is about to cross the members of the cross line will be closed, thus closing the gap which would otherwise be made by the wheel-flange gaps 40 of the crossing rails, the parts occupying this position until the traffic is opened up on the cross line. It is also proposed to construct these movable members so that if the 45 automatic connections fail to operate the flanges of the wheels will operate said members thus eliminating derailing.

In a more specific embodiment of the invention laterally movable angular rail members are arranged at each intersection, and 50 these constitute the guard rails for one line and act when displaced toward their component traffic rails to fill or close the gaps in the traffic rails of the crossing line so that the traffic rails of the crossing line are made 55 continuous. It is obvious that there will be two pairs of these members for each line and it is proposed to so connect these that when one pair in a line is operated the other pair in the same line will be automatically operated and at the same time the members 60 of the crossing line will be operated.

The invention will be more readily understood from a reading of the following specification and by reference to the accompanying drawings, in which an example of the invention is illustrated, and wherein—

Figure 1 is a plan view of a crossing constructed in accordance with this invention,

Fig. 2 is a cross sectional detail view taken on the line 2—2 of Fig. 1, 70

Fig. 3 is an enlarged detail in plan of one of the intersections, and

Fig. 4 is a plan view of a modified form of crossing.

In the drawings the numeral 1 designates 75 one line or track and 2 the crossing line or track. It is evident that the tracks may cross each other at various angles, but as the greater number of crossings are at right angles we will first describe the invention 80 as applied to such a crossing. Track 1 comprises two traffic rails, each comprising sections 3, 4 and 5; while track 2 comprises two traffic rails each also comprising three sections 6, 7 and 8, which are counterparts of 85 the corresponding sections of the other track, whereby the sections are interchangeable. At the center of the crossing guard rails 9 are disposed parallel with sections 4 and at right angles to guard rails 10 which are 90 parallel with sections 7. Longitudinally of the sections 3, 5, 6 and 8 respectively laterally displaceable angular guard members 11, 12, 13 and 14 are disposed. A description 95 of one of these members will be sufficient 100 for all. Each member has a laterally directed wing 15 which is disposed at such an angle that it may be swung into contact with the chamfered or tapered end 16 of the adjacent section of the traffic rail of the crossing line. The wing 15 extends at an angle from a head portion 17 joined on to the guard rail portion of said member and occupies the space between the chamfered end 105 of the traffic rail section and the end of the adjacent traffic rail section of the same track. The member as stated is capable of lateral movement whereby its head portion may be swung to close the gap in the crossing track. The member is suitably pivoted at 18 and 110 carries stop lugs 19 confined in keepers 20 which limit the displacement of said mem-

ber away from the traffic rail section of its line. All of the parts described are mounted on crossing plates 21 suitably supported on ties or other foundation.

5 By referring to Fig. 1 it will be seen that the angular guard rail members 11 and 12 are swung over against the traffic rail sections 3 and 5 respectively, whereby the wings 15 are in contact with the chamfered ends 16 of the traffic rail sections 7 of the crossing track or line 2; while the heads 17 close the gaps between the ends 16 and the adjacent traffic rail sections 6 and 8. From this it will be seen that the traffic rails of the 10 line 2 are continuous and unbroken so that the wheels of a train in passing over the crossing on track 2 will have a continuous rail and will not be subjected to the jar and vibration which would be encountered in 15 the usual crossing where wheel flange gaps are left in the traffic rails of line 2 for the wheels passing over the rails of track 1. Again referring to Fig. 1 it will be seen that the angular guard rail members 13 and 14 20 respectively are swung away from the traffic rail sections 6 and 8 and against their keepers 20 so as to be moved out of the path of the wheel-flanges of the train using track 2.

With the parts in this position track 2 is 30 open for traffic approaching the crossing in either direction while track 1 is closed. It is apparent that when it is desired to open track 1 for traffic the angular guard rail members must be adjusted so as to close 35 track 2 and bridge the gaps in the traffic rails of track 1. It will be seen that the flanges of wheels approaching the members 11 or 12 of the track 1 will displace said members inward upon coming in contact with the same and it is obvious that by 40 properly connecting all of the said angular members they may be automatically and simultaneously adjusted. For instance if the members 11 are acted upon and disposed inward the connections would be such as to also move the members 12 inward and vice versa. At the same time the members 13 and 14 would be swung outward, reference being had to the center of the 45 track. This operation would be reversed if the approach was made on track 2 and the same was closed.

As an example of connections for automatically shifting the angular guard rail members we have shown each pair of guard members provided with bell crank levers 22 and 23 respectively. Each lever is linked to the end of a guard rail member at one end, while the opposite end of each lever 50 22 is connected with the opposite end of its companion lever 23 by a link 24. The ends of the levers connected by the link 24 form with the said link a toggle-joint so that each pair of levers are swung toward each other 55 or away from each other when operated,

whereby the wings 15 of each pair of angular guard rail members are swung toward each other or away from each other when their toggle-joint is operated. Each lever 23 has an arm 25 which is pivoted at its 70 outer end to the end of the pitman 26 extending at substantially right angles thereto. Each pitman has connection with a bell crank lever 27.

It will be seen that there are four toggle-joints each connected with the other by means of the parts 25, 26 and 27 and arranged to operate simultaneously. It is pointed out, however, that the toggle-joints for operating the members of one track are 80 reversely connected with relation to the toggle-joints for the other track, whereby the operation of the joints of one track will be opposite to those of the other track. This is accomplished by reversing the disposition 85 of the short legs of the corresponding levers of the two tracks as is clearly illustrated. Referring to Fig. 1 it will be seen that the short legs of the levers 22 of the track 1 are directed relatively inward or 90 toward the center of the crossing, whereas the short legs of the levers 22 of the track 2 are directed relatively outward or away from the center of the crossing and the same relative disposition is true of the levers 23. 95

As before stated it is evident that the angles of crossings vary and in Fig. 4 we have shown tracks crossing each other at several degrees off of a right angle, and the only difference in this and the right angular 100 crossing lies in the particular formation of the parts, the operation and principle being the same. It is obvious that variations would be necessary for crossings at different angles. However the angular guard members in the form illustrated in the Fig. 4 just referred to are slid able instead of being pivoted. This is necessary on account of the acute and obtuse angles incidental to the crossing. In the said Fig. 4 we have also 105 shown tracks 1 and 2, and we have shown track 1 as having traffic rails comprising sections 3', 4', and 5' and track 2 as having traffic rails comprising sections 6', 7' and 8'; while the track 1 has angular guard rail members 11', and 12', 13', and 14'. The track 1 has guard rails 9' and the track 2 guard rails 10'. The parts are numbered so as to show their analogy to the similar parts of Fig. 1. As shown in the Fig. 4 track 1 is 110 closed and track 2 is open. The intermediate traffic rail sections also have chamfered ends 16', and the angular guard rail members also have wings 15', stop lugs 19' working in keepers 20'. It is pointed out 115 that the angular guard rail members will necessarily have different shapes but they are generic in construction. Each of said members abuts a fixed guard rail section 30 and is arranged to slide transversely of the 120

130

same toward and away from its adjacent traffic rail section. Each member carries a rail arm 31 having spring pressed connection at 32 with the adjacent rail 30, so that when 5 said member is displaced from its adjacent rail section it is moved against the tension of said spring device which acts to return the member when said member is released.

From the outer end of the wing 15' of 10 each angular member a pivoted link 33 extends and is pivoted on a crossing plate 34 as shown. The function of these links is to guide and swing the wings so that they will align with the chamfered ends 16'. The 15 same form of connections for operating the angular guard rail members are used in this crossing as are employed for the crossing shown in Fig. 1, and comprise parts 22', 23', 24', 25', 26' and 27' which correspond to the 20 similar parts in Fig. 1. A detailed explanation of the same together with their operation is considered unnecessary.

As a safety feature the corner at the outside angle of each angular guard rail member is beveled as indicated at 35 and should the toggle-joint connections fail to operate it is obvious that the wheel-flanges will strike these beveled portions and displace the members thus preventing derailment. 30 This is a very important feature and reduces the liability of accident.

The foregoing description and illustration clearly express the invention, but it is to be understood that said illustration is 35 merely an exemplification and the invention may be carried out in various other ways.

What we claim; is,

1. In a railroad crossing, traffic rails crossing each other at an angle, each rail 40 comprising approaching sections with an intermediate section therebetween having chamfered ends and gaps between the ends of the intermediate section and the approaching sections, angular guard members 45 each having one wing between one of the approaching rail sections and the correlated chamfered end of its intermediate section, said member being movable from its approaching rail section to provide a wheel flange gap therebetween for the crossing rail, the other wing of each member constituting a guard rail along the approaching 50 section of the crossing rail, and a central guard rail parallel with each intermediate 55 rail section and projecting beyond the chamfered ends of the same and opposite the wings of the movable guard members at the ends of said intermediate rail section, the central guard rails having their ends joined 60 together, all of the rails sections, guard rails and movable guard members being formed of standard T-shaped rails, one of

the lines of traffic being constantly open for the flanges of the wheels passing thereover.

2. In a railroad crossing, traffic rails crossing each other at an angle, each rail comprising approaching sections with an intermediate section therebetween having chamfered ends and gaps between the ends of the intermediate section and the approaching sections, angular guard members each having one wing between one of the approaching rail sections, and the correlated chamfered end of its intermediate section, the other wing of each member constituting 70 a guard rail along the approaching rail section of the crossing rail, the guard members being arranged in pairs at each intersection of the crossing rails and one of the members of each pair being normally spaced from the 75 approaching rail for which it forms a guard, while the other is bridging the gap between said approaching rail section and the ends of its correlated intermediate section, said members being movable to reverse their disposition with relation to the approaching rail sections, and a common operating means connected with all of the movable guard members arranged to move one member of each pair to close the gap and the other to 80 open it.

3. In a railroad crossing, traffic rails crossing each other at an angle, each rail comprising approaching sections with an intermediate section therebetween having chamfered ends and gaps between the ends of the intermediate section and the approaching sections, angular guard members each having one wing between one of the approaching rail sections, and the correlated chamfered end of its intermediate section, the other wing of each member constituting a guard rail along the approaching rail section of the crossing rail, the guard members being arranged in pairs at each intersection 95 of the crossing rails and one of the members of each pair being normally spaced from the approaching rail for which it forms a guard, while the other is bridging the gap between said approaching rail section and the ends of its correlated intermediate section, said members being movable to reverse their disposition with relation to the approaching rail sections, and a common operating means connected with all of the movable guard members arranged to move one member of each pair to close the gap and the other to 100 open it.

In testimony whereof we affix our signatures.

THOMAS J. O'CONNOR.
WARREN W. CULBERTSON.
